Inventor

UNITED STATES PATENT OFFICE.

GEORGE L. RICHARDSON, OF BRUNSWICK, MAINE.

FIRE-KINDLER.

SPECIFICATION forming part of Letters Patent No. 417,588, dated December 17, 1889.

Application filed August 31, 1889. Serial No. 322,575. (No model.)

To all whom it may concern:

Be it known that I, GEORGE L. RICHARDSON, a citizen of the United States, residing at Brunswick, in the county of Cumberland and State of Maine, have invented a new and useful Fire-Kindler, of which the following is a specification.

The invention relates to improvements in fire-kindlers.

The object of the present invention is to produce a fire-kindler of simple and economic construction, which will enable liquid hydrocarbons to be used with perfect safety in lighting fires, and which need not be removed from the stove until after the fire has gone out.

The invention consists in the novel combination and arrangement of parts hereinafter fully described, illustrated in the accompanying drawings, and pointed out in the claims hereto appended.

In the drawings, Figure 1 is a perspective view of a fire-kindler constructed in accordance with the invention. Fig. 2 is a central vertical sectional view.

Referring to the accompanying drawings, A designates a metallic casing or box composed of the bottom a , which is preferably a disk, but may be square, triangular, or any other desirable shape, and the sides, which rise from the base, and are preferably curved, and a perforated top or follower a^2 , suitably secured within the sides a' . The casing or box is filled with asbestos, brick, or some other indestructible substance that will absorb a liquid hydrocarbon, and then the perforated top is secured in place and the device is ready for use; but in order to prevent the wood lying too close to the perforations and choking the fire vertical flanges B are provided. The vertical flanges B are secured to the per-

forated top or follower a^2 , and are preferably four in number and extend out radially from a tube C. The tube C is formed integral with the top or follower, and passes through a central opening in the latter and serves as a central support, and is provided at its lower end with openings c' , which supply air and aid combustion, and also aid in filling the device with oil.

From the foregoing it will readily be seen that fire-kindlers made in accordance with this invention are simple and cheap in construction and require very little oil to start a fire; that they can be used with perfect safety, and can be allowed to remain in the stove until the fire has gone out and it is necessary to refill them.

What I claim is—

1. A fire-kindler comprising the box or casing composed of the bottom a and the sides a' , the filling of asbestos or similar indestructible material, the perforated follower or casing, and the vertical flanges extending out radially from the top of the tube, substantially as described.

2. A fire-kindler comprising the box or casing, the filling of asbestos or similar indestructible material, the perforated top or follower, the central tube formed integral with the top or follower and provided with openings in its lower end, and the vertical flanges extending outwardly from the tube, substantially as described.

In testimony that I claim the foregoing as my own I have hereto affixed my signature in presence of two witnesses.

GEORGE L. RICHARDSON.
